HEAD ATTACHED BALANCING TOY
Ally O. Hing, P.O. Box 607, Superior, Ariz.
Filed Mar. 26, 1962, Ser. No. 182,424
5 Claims. (Cl. 273—97)

The present invention generally relates to a toy, and more particularly to a toy normally positioned on the head of the user and activated by the use of various body motions such as twisting, bouncing or jumping.

One of the primary objects of the present invention is the provision of a toy which will afford many hours of enjoyment to the user thereof.

Another object of the present invention is the provision of a toy which requires only a minimum amount of space for the use thereof, thus resulting in a toy which can be used indoors as well as outdoors.

A further object of the present invention is the provision of a toy which can be adjusted in accordance with the varying ability of the user or users thereof.

Additionally, an object of the present invention is the provision of a toy which can be used while partaking in various other amusements, such as dancing, foot racing, or other conventional games, so as to require the exercise of a greater amount of skill thus further increasing the challenge of these other means of amusement.

Also, an object of the present invention is the provision of a toy which is completely safe for the user thereof, relatively inexpensive to manufacture, simple to use, and practically indestructible during the use thereof.

A final object to be specifically enumerated herein is the provision of a toy which comprises a resilient springy device having a first end which is engaged over the head of the user, a loosely wound spiralled center section, and a receptacle secured to the upper end of the spiralled center section loosely receiving an object therein capable of being thrown out of the receptacle and subsequently again received therein through the expansion and contraction of the resilient member induced by various movements of the body of the user.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the toy comprising the present invention in its normal or at rest position;

FIGURE 2 is a front elevational view of the present invention illustrating the device in its contracted position about the head of the user;

FIGURE 3 is a plan view of the device of the present invention with the receptacle removed therefrom;

FIGURE 4 is a partial sectional view taken substantially on a plane passing along line 4—4 in FIGURE 1; and

FIGURE 5 is a partial elevational view of the lower head engaging section of the toy of the present invention.

Referring now more particularly to the drawings, reference numeral 10 generally designates the toy comprising the present invention. The toy of the present invention consists basically of three sections, a lower head engaging section 12, a central resilient or springy section 14, and an upper object receiving section 16. The lower section 12 and central section 14 comprise a plurality of integral convolutions formed of metal, plastic or any other suitable material.

The lower section 12 consists of a plurality of tightly wound coils 18 shaped so as to conform to the head 20 of the user thereof. The upper coil 22 terminates in an outwardly winding and loosely wound portion 24 which

2

is integrally formed with the lower enlarged coil 26 of the loosely wound spiralled central section 14, which in turn is composed of a plurality of upwardly diminishing coils 28. The upper one of the coils 28 terminating in an outwardly angled end 30 provided with a threaded outer surface 32 for engagement with an internally threaded boss 34 on a receptacle 36 forming the upper section 16 of the device 10. It will be noted that the receptacle 36 can also be formed of metal, plastic, or any other suitable material, and additionally, may be secured to the outwardly extending end portion 30 in any conventional manner.

An object 38, preferably a non-resilient ball, is generally located within the receptacle 36, and if so desired, may be attached thereto by an elongated string-like member 40 attached to the receptacle in any convenient manner such as extending the end of the string-like member 40 through an aperture 42 and providing a knot 44 on the end thereof.

Additionally, attention is directed to the fact that the device 10 of the present invention can be formed of an elongated hollow plastic member, as best illustrated in FIGURE 4, provided with a valve means 46 communicating with the interior 48 of the tubular member and providing a means for the introduction of air thereto so as to vary the amount of resiliency or springiness in the central section 14. It will also be noted that the upper end of the angled end portion 30 is open and adjustably sealed by the removable receptacle 36, thus allowing for the introduction of water into the hollow interior 48 so as to provide a second means for varying the amount of resiliency. Being able to increase the resiliency of the device will enable the user thereof to make the operation thereof increasingly more difficult as his skill increases thereby providing a continuous challenge. As is readily apparent, the use of air or water pressure to increase the resiliency of the toy of the present invention requires that the hollow plastic convolutions be formed of relatively soft plastic only sufficiently rigid so as to provide a minimum amount of resiliency, thereby enabling the use of the device either with or without the additional pressure while still providing for a wide range of variance in the resiliency thereof by the introduction of increasing amounts of pressure.

As best seen in FIGURE 2, the convolutions of the central section 14 are of such width so as to allow the device to completely encompass the head of the user upon being compressed downwardly thereby preventing any undesirable contact while maintaining the maximum amount of springing action. The provision of an enlarged lower coil 26 along with upwardly decreasing coils 28 on the central section 14 results in a device having a low center of gravity thereby facilitating the balancing of the entire device upon the user's head.

From the foregoing, the manner in which the toy of the present device is used is considered to be readily apparent. The lower section of the toy consists of a plurality of tightly wound convolutions adapted to engage the head of the user. Integrally secured to and formed as a continuation of the head engaging section, is the central resilient section formed of a plurality of convolutions loosely wound in an upwardly decreasing spiral, the majority of these central section convolutions being of a size so as to allow the central section to, upon compression thereof, encompass the head of the user. It will be noted that this center section responds to the movement of the body of the user so as to reciprocate in a manner tending to discharge an object loosely positioned within a receptacle secured to the upper end of the central section thereby requiring a great degree of agility in order to return the discharged article to the receptacle. In addi-

tion to being used in itself as a source of amusement, it is also contemplated that the present device be worn by the participants in various other conventional games involving movement, such as races, for the purpose of increasing the difficulty of such games. Also of significance, is the fact that, in one modified form of the present invention, the resiliency of the device can be varied so as to continue to present a challenge to the user thereof.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A balancing toy comprising a unitary resilient spring device provided at a first end with a head engaging section formed of a plurality of tightly wound convolutions, and a central section formed of a plurality of loosely wound convolutions, said central section being substantially in the form of an upright spiral having an enlarged base and terminating in an object receiving upper section, the uppermost convolution of the head engaging section ending in an outwardly directed loosely wound convolution terminating in and integrally formed with the enlarged base of the spiral so as to allow for a vertical movement of that portion of the spring device above the head engaging section, said central section being of a size as to allow for its movement down about the head engaging section without contact therewith.

2. The device of claim 1 including means for varying the degree of resiliency of the resilient spring device.

3. A balancing toy comprising a unitary resilient spring device provided at a first end with a head engaging section formed of a plurality of tightly wound convolutions, and a central section formed of a plurality of loosely wound convolutions, said central section being substantially in the form of an upright spiral having an enlarged base and terminating in an object receiving upper section,

5

the uppermost convolution of the head engaging section ending in an outwardly directed loosely wound convolution terminating in and integrally formed with the enlarged base of the spiral, said spring device consisting of a hollow tubular member sealed at both ends and valve means for the introduction of air into the interior of the tubular member.

10 4. The device of claim 1 wherein the object receiving upper section consists of an upwardly opening receptacle, an object being secured thereto by an elongated string-like member.

15 5. A balancing toy comprising a resilient spring device provided at a first end with a head engaging section, a resilient central section formed of a plurality of loosely wound convolutions, said central section being substantially in the form of an upright spiral having an enlarged base and terminating in an object receiving upper section, and a resilient outwardly directed loosely wound convolution secured to end extending from the top of the head engaging section to the lowermost convolution of the central section so as to allow for a vertical movement of that portion of the spring device above the head engaging section, said central section being of a size so as to allow for its movement down about the head engaging section without contact therewith.
